UNITED STATES PATENT OFFICE.

DE WITT C. PRESCOTT, OF MARINETTE, WISCONSIN.

SETTING MECHANISM FOR SAW-MILLS.

SPECIFICATION forming part of Letters Patent No. 257,757, dated May 9, 1882.

Application filed February 18, 1881. (No model.)

To all whom it may concern:

Be it known that I, DE WITT C. PRESCOTT, a resident of Marinette, in the county of Marinette and State of Wisconsin, have invented 5 certain new and useful Improvements in Setting Mechanism for Saw-Mills, which are fully set forth in the accompanying specification, reference being had to the accompanying drawings, in which—

10 Figure 1 is an end elevation of a log-carriage and head-block with my improved setting mechanism applied; Fig. 2, a plan view of the same, only so much of the carriage being shown as is necessary to illustrate the setting mechanism; 15 Fig. 3, a detailed side elevation of the setting mechanism; Fig. 4, a transverse section of the same, taken on the line *yy*, Fig. 3; Fig. 5, a longitudinal section taken on the line *xx*, Fig. 2, looking from the inside; Fig. 6, a transverse 20 section taken on the line *zz*, Fig. 5; Fig. 7, a detached view of the spring-pawl mechanism on an enlarged scale; Fig. 8, a plan view of the same; and Fig. 9, a transverse section taken on the line *vv*, Fig. 3, showing the shipping mechanism.

25 My invention relates to setting mechanism for adjusting the log on the carriage as one piece after another is dropped by the saw, the object of my improvement being to provide 30 mechanism for setting the knees on the head-blocks transversely to the carriage with a certain and accurate graduation.

The invention consists in certain special 35 mechanism and combinations of devices for accomplishing the above-stated purpose. The construction and operation of this device will be hereinafter fully described, and the special 40 improvements which it is believed are new, and which it is desired to secure by Letters Patent, will be more definitely pointed out in the claims.

In the drawings, A represents the carriage, which is of any ordinary construction, and B the head-block at one end of the carriage.

45 A knee, C, of common construction, is mounted on the head-block and arranged to slide thereon transversely to the carriage in the usual way, suitable ways being provided for this movement.

50 The knee on the head-block is moved back and forth by a screw-shaft, D, carrying on its

outer end a beveled pinion, d. A four-inch pitch is preferably given to the screw-thread on this shaft, though I do not limit myself to this precise construction.

55 The beveled pinion *d* meshes with a similar pinion, e, on the end of the main setting-shaft E, which runs lengthwise of the carriage, being mounted in suitable bearings at the side thereof.

60 A pawl-carrier, F, is secured to the shaft E a short distance in front of the head-block. In the drawings it is shown fastened to the shaft by a key, f, or any other suitable device 65 may be employed.

65 On the rear side of the pawl-holder is a ratchet-wheel, G, and on the front side thereof is a similar wheel, H. Both of these wheels, which are mounted loosely on the shaft, are cap-shaped and arranged to inclose the pawl-carrier, and are provided with internal ratchet-teeth, g h.

70 A pawl, I, is pivoted to the face of the pawl-carrier, being arranged on the back portion thereof so as to engage with the ratchet-teeth of the wheel G, as shown in Fig. 6 of the drawings. A portion of the width of this pawl, on the inside thereof, is extended back of the pivot to form a tail-piece, i.

75 A suitable spring, i', is arranged in a socket, i', underneath the outer end of the pawl to cause it to engage with the ratchet-wheel.

80 A similar pawl, J, is mounted in the same way on the opposite side of the pawl-holder and arranged to engage with the ratchet-teeth 85 of the wheel H. It is provided with a tail-piece, j, and a spring, j', within a socket, j', in precisely the same way as the pawl I.

85 The tails of the two pawls extend backward side by side, as shown in Fig. 8 of the drawings, and directly underneath them is a vertical socket, f', in the pawl-holder, within which is placed a loose pin, f'', the head of which, at the upper end, is sufficiently large to extend directly underneath the tails of both pawls. 90 The lower end of this pin enters a longitudinal groove, e, in the shaft E, and in this groove is fitted a slide, K, the inner end of which is beveled and passes underneath the lower end of the pin, as shown in Fig. 5 of the drawings. 95 This slide passes out beyond the hub of the wheel G, and is provided with a collar, k, at-

tached to its outer end and arranged to slide on the shaft, being provided with an annular groove, k' .

A vibrating frame or toggle, L , is mounted 5 in suitable bearings on the carriage-frame directly opposite the ratchet-wheels, so as to have a free vertical vibration. This frame is branching, having an outside arm on each side extending toward the ratchet-wheels, the rear 10 one, l , being higher than the forward one, l' . It is also provided with a central arm, l^2 , which is wider than the others and extends from the plane of one to the plane of the other.

On the under side of the ratchet-wheel H is 15 a lug, h' , and a pitman or connecting-rod, M , is pivoted at one end to this lug and at the other to the lower arm, l' , the pivoted part running from the latter to the lower portion of the central arm, l^2 .

20 A similar lug, g' , is provided on the upper portion of the wheel G , and a connecting-rod or pitman, N , is pivoted at one end to this lug and at the other to the upper arm, l , being also connected in a similar way to the central arm, l^2 .

25 A hand-lever, O , is fastened in any suitable way to the ratchet-wheel H , and just in front of it is arranged an arc, P . This arc is supported at its outer end by the shaft E , being mounted by a sleeve, p , on the outer end of 30 the hub of the wheel H .

The inner end of the arc is extended to the frame in a web and may be cast in one piece with the plate forming bearings for the vibrating toggle, or may be made separately, if desired.

35 The face of the arc next the lever is provided with a graduated scale, p , and a series of pins, p^2 , are arranged in sockets in the arc, so that they may be projected on this scaled face.

40 The lever O is set a little way from the arc, and is provided with a spring-stop, o , which rests against the graduated arc and is arranged to strike against the stop-pins when one is turned out in its path.

45 At the inner end of the arc is one pin which always remains projected, so as always to stop the lever at a certain point when turned inward toward the carriage.

50 A yoke or fork, Q , is attached to a vertical shaft, q , mounted in a suitable bracket on the carriage-frame.

The yoke is arranged to embrace the collar k , as shown in Fig. 9 of the drawings, and 55 the upper end of the shaft is provided with a handle, R , by means of which it may be oscillated, thereby moving the slide back and forth on the shaft.

60 The operation of this mechanism is as follows: Obviously, whenever the lever O is vibrated, thereby oscillating the ratchet-wheel H , the toggle L will also be vibrated, thereby causing a similar oscillation of the wheel G , but in the opposite direction. It is also evident that the inward oscillation of the wheels 65 engages the teeth with the respective pawls,

thereby communicating motion to the shaft E , while on the outward oscillation the teeth will slip over the pawls and the movement be ineffective. Hence on the working oscillation of 70 one of the ratchet-wheels the other is moving idly. Now, the pins on the graduated scale are so arranged relatively to the number of teeth on the ratchet-wheels, the teeth on the gear-pinions, and the pitch of the screw that 75 they become indicating-stops to determine the precise movement of the lever in order to set the log for any required thickness of lumber, and the arrangement is such that the movement of the lever in one direction accomplishes 80 one half of the set and in the other direction the other half. For instance, preferably the lever is always in a state of rest at its upper point of vibration or against the permanent stop-pin, as shown in Fig. 1 of the drawings. Now, when it is desired to set the log 85 the lever is pulled forward or outward until it strikes the graduating-pin, thereby giving the wheel G an effective movement and turning the shaft E half the distance for the required 90 set. The lever is then turned back into its first position, reversing the movement of the ratchet-wheels, and causing the wheel H to finish the set.

When it is desired to release the pawls for 95 the purpose of reversing the setting-shafts the slide K is thrust inward, thereby lifting the loose pin and raising the tail-pieces of the pawls until the working ends of the latter are finally disengaged from the ratchets. The 100 screw-shaft D is provided with a hand-wheel, S , for the purpose of accomplishing this reverse movement, if desired.

I have described my setting mechanism applied to setting screws for reciprocating the 105 knees, but I do not limit myself to this device, for obviously a rack and pinion may be substituted for the screws with such slight changes in adaptation as will be obvious to any mechanician familiar with mechanism of this kind. 110

I am aware that a single ratchet-wheel and double pawls have been employed in setting mechanism, the wheel being fastened to the shaft.

With my improvement I am enabled to obtain 115 a nice graduation and great accuracy in the set, especially with the double movement of the lever required to make a full set. And my device also enables me to inclose the ratchet mechanism, so that it is protected from 120 obstructions and derangement.

The arrangement of the toggle-arms in different places avoids all danger of dead-points, so that the setting-lever is never stuck. It will be understood of course that the carriage 125 is provided with additional blocks and knees, as may be required, the shaft E being provided with pinions engaging with similar pinions on the screw-shaft at each block, the same as already described for the block shown.

130 I do not wish to be understood as limiting myself to details of construction in all par-

ticulairs as described above, for my improved device may be modified in many details without departing from my particular mode of construction and operation.

5 I am aware of Letters Patent No. 199,667, granted E. H. Stearns, January 29, 1878, and I expressly disclaim all devices and combination of devices shown and described in the said Letters Patent, restricting myself to the differences between my apparatus and that shown in this patent and others of earlier date.

Having thus described my invention, what I claim as new, and desire to secure by Letters Patent, is—

15 1. In a setting mechanism for saw-mills, the knees and connections, in combination with a pawl-carrier fastened to the shaft by which the knees are adjusted, two ratchet-wheels mounted loosely on the same shaft and surrounding the carrier, and connecting mechanism, substantially as described, operated by a lever, whereby the vibration of the latter causes the ratchet-wheels to oscillate in opposite directions and engage alternately with their respective pawls on the carrier, substantially as and for the purposes set forth.

20 2. The pawl-carrier F, mounted rigidly on the actuating-shaft, in combination with the ratchet-wheels G and H, mounted loosely on said shaft and arranged around the carrier, the pawls I and J on the carrier, the vibrating toggle L, the pitmen M and N, the knees C, and mechanism connecting the latter with the actuating-shaft, whereby the knees are adjusted 35 by the movement of the shaft, substantially as and for the purposes set forth.

25 3. In a setting mechanism for saw-mills, the ratchet-wheels G and H, mounted on the shaft from which motion is communicated to the adjustable knees, in combination with the pitmen M and N, the vibrating toggle L, constructed with sections in different planes, to each of which one of said pitmen is connected, and an operating-lever, substantially as and for the purposes set forth.

40 4. The actuating-shaft of a setting mechanism for saw-mills, in combination with a pawl-carrier rigidly attached thereto and provided with suitable pawls, the ratchet-wheels mounted loosely thereon, the toggle L, provided with the arms l' in different planes, and the central web-arm, l'', and the pitmen M and N, substantially as described.

5 The actuating-shaft of a setting mechanism for saw-mills, in combination with the 55 pawl-carrier F, rigidly secured thereto, the pawls I and J, mounted thereon and provided with tail-pieces i j, the loose pin f'', arranged on the carrier underneath the tail-pieces of the pawls, and mechanism whereby the pin may 60 be lifted to turn the pawls on their pivots and disengage them from the ratchet-wheels, substantially as described.

6. The actuating-shaft of a setting mechanism for saw-mills, in combination with the 65 pawl-carrier F, rigidly secured thereto, the pawls I and J, mounted thereon and provided with tail-pieces i j, the loose pin f'', arranged on the carrier underneath the tail-pieces of the pawls, the beveled slide K, arranged in a 70 groove in the shaft, and mechanism for reciprocating the latter, substantially as and for the purposes set forth.

7. The actuating-shaft of a setting mechanism for saw-mills, in combination with the 75 pawl-carrier F, rigidly secured thereto, the pawls I J, mounted thereon and provided with tail-pieces i j, the springs i' j', arranged in sockets in the carrier under the working ends of the pawls, the loose pin f'', arranged on the 80 carrier underneath the tail-pieces of the pawls, and mechanism for raising said pin, substantially as and for the purposes set forth.

8. In a setting mechanism for saw-mills, the knees and connections, in combination with a 85 pawl-carrier fastened to the shaft by which the knees are adjusted, the two pawls mounted on said carrier, the two loose ratchet-wheels mounted on said shaft and surrounding the carrier and pawls, mechanism connecting the 90 two ratchet-wheels, whereby the oscillation of one will cause the other to oscillate in the opposite direction, a lever for oscillating one of the ratchet-wheels, and a graduated series of stops, all arranged and operating, substantially 95 as described, to make half the set by the vibration of the lever in one direction and the other half by its return movement, both these movements being determined by the adjustment of the stops.
